(57) **CLAIM**

The ornamental design for a display screen with graphical user interface, as shown and described.

DESCRIPTION

FIG. 1 is a front view of a display screen with graphical user interface; and,

FIG. 2 is an enlarged view of the delimited portion labeled as "2" in FIG. 1.

The dash-dash broken lines showing the display screen form no part of the claimed design. The remaining dash-dash broken lines showing portions of the graphical user interface form no part of the claimed design.

The dot-dash broken line rectangle illustrating the bounds of the enlarged view and the dot-dash lead line labeled 2 indicates the area from which the enlargement is taken and form no part of the claimed design.

1 Claim, 2 Drawing Sheets
